CLAIM

The ornamental design for a pant with anatomy enhancing pockets, as shown and described.

DESCRIPTION

FIG. 1 is a front elevational view of a pant with anatomy enhancing pockets showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, left side perspective view thereof, showing our new design being worn with additional unclaimed environment;

FIG. 8 is a rear, left side perspective view thereof; and,

FIG. 9 is a rear perspective view thereof.

The broken lines shown in FIGS. 1-9 represent environmental structure and portions of the article that form no part of the claimed design.

1 Claim, 6 Drawing Sheets
